United States Patent Office

Des. 217,973
Patented July 7, 1970

217,973

GAME BOARD

Frank Kohner and Natalie Donna, New York, N.Y., assignors to Kohner Bros., Inc., Paterson, N.J., a corporation of New York

Filed Jan. 27, 1969, Ser. No. 15,509

Term of patent 7 years

Int. Cl. D21—01

U.S. Cl. D34—5

FIG. 1

FIG. 2

FIG. 3

FIG. 4

FIG. 1 is a top view of the game board;

FIGS. 2 and 3 are front and bottom views of the game board; and

FIG. 4 is a fragmentary sectional view through the game board and illustrating a portion of a scoring wheel.

We claim:

The ornamental design for a game board, substantially as shown and described.
